US00D702873S

(12) **United States Design Patent**
Yu

(10) **Patent No.:** **US D702,873 S**
(45) **Date of Patent:** **** Apr. 15, 2014**

(54) **REFLEX PLATE**

(75) Inventor: **Feng Yu**, Ningbo (CN)

(73) Assignee: **Ningbo Yinzhou Self Photoelectron Technology Co., Ltd.**, Ningbo (CN)

(**) Term: **14 Years**

(21) Appl. No.: **29/404,943**

(22) Filed: **Oct. 27, 2011**

(30) **Foreign Application Priority Data**

Sep. 16, 2011 (CN) 2011 3 0325389

(51) **LOC (10) Cl.** **26-99**

(52) **U.S. Cl.**

USPC **D26/123**

(58) **Field of Classification Search**

USPC D26/122, 118, 2, 28, 142, 123, 124, 35;

Primary Examiner — Kevin Rudzinski

(57) **CLAIM**

The ornamental design for a reflex plate, as shown.

DESCRIPTION

FIG. 1 is a front elevational view of a reflex plate of my new design;

FIG. 2 is a rear elevational view of the reflex plate;

FIG. 3 is a top plan view of the reflex plate;

FIG. 4 is a bottom plan view of the reflex plate;

FIG. 5 is a left side elevational view of the reflex plate;

FIG. 6 is a right side elevational view of the reflex plate; and,

FIG. 7 is a perspective view of the reflex plate.
